UNITED STATES PATENT OFFICE.

JOSEPH WIESBAUER, OF BUFFALO, NEW YORK.

JEWELER'S CARD AND TAG CABINET.

SPECIFICATION forming part of Letters Patent No. 271,007, dated January 23, 1883.

Application filed August 8, 1882. (No model.)

To all whom it may concern:

Be it known that I, JOSEPH WIESBAUER, of Buffalo, in the county of Erie and State of New York, have invented certain new and useful Improvements on a Jeweler's Card and Tag Cabinet; and I do hereby declare that the following description of my said invention, taken in connection with the accompanying sheet of drawings, forms a full, clear, and exact specification, which will enable others skilled in the art to which it appertains to make and use the same.

This invention has general reference to jewelers' card and tag cabinets; and it consists essentially in the novel and peculiar combination of parts and details of construction, as hereinafter first fully set forth and described, and then pointed out in the claims.

In the drawings already mentioned, which serve to illustrate my said invention more fully, Figure 1 is a perspective view of my improved tag and card cabinet. Fig. 2 is a plan of the same with the cover and tag-tray removed. Fig. 3 is a transverse sectional elevation in line *xx* of Fig. 2, and Fig. 4 is a longitudinal sectional elevation in line *yy* of Fig. 2.

Like parts are designated by corresponding letters of reference in all the figures.

A in these drawings represents a box-like structure, having a hinged cover, B, provided with a clasp or other locking or closing device, Q, engaging a correspondingly-constructed mechanism, &c., R, as clearly illustrated in Fig. 1. In the interior of this box I provide a number of longitudinal partitions, D E, respectively, and a series of transverse partitions, F G, respectively, thereby dividing the interior of said box into a series of compartments for the reception of jewelers' cards L, Fig. 4, said partitions being so disposed as to cause the said compartments to assume different lengths, (respectively widths,) in order to accommodate differently-sized cards. "Jewelers' cards," so called, are rectangular pieces of card-board having a number of slits to receive the backs of cuff and collar buttons, &c. They are of various lengths and widths, according to the size of jewelry to be accommodated, and they are furthermore frequently renewed,

owing to the fact that in exhibiting jewelry 50 they are soon soiled, and when the articles of jewelry are removed and replaced soon worn out. Jewelers therefore keep a number of blank cards on hand to replace soiled and worn ones; and to provide for a suitable receptacle for these spare cards, which is the object of my present invention, I have constructed the device in consideration.

In the partitions D E, I have provided a series of notches, O, to enable the removal of 60 the cards from the compartments, and to enable the withdrawal of the narrow cards as readily as the widest ones I provide the respective compartments with lining or filling blocks J K, so as to bring all the cards into one level 65 surface.

The partitions D, E, F, and G do not reach up to the level M of the box A, but stop short thereof sufficiently to enable said box to receive the lower part of a tray, C, in such manner as to allow said tray to rest upon the upper edges, N, of said partitions, and to be partially embraced by the upright walls of said box. In this tray C, I provide longitudinal and transverse partitions H I I', respectively, 70 thus dividing said tray into a number of receptacles for jewelers' tags or other similar articles, there being provided a ring or other analogous device, P, for lifting the tray out of the box A to obtain access to the cards.

By constructing a tag and card cabinet in the manner described I have succeeded in producing an article of manufacture which supplies a long-felt want, and which, owing to its cheapness, can be sold at a very low figure. As a matter of course, this cabinet can be produced from either cheap or expensive wood, at the option of the manufacturer, and ornamented in any desired style at the pleasure of the producer.

Having thus fully described my invention, I claim as new and desire to secure to me by Letters Patent of the United States—

1. The box A, having cover B, tray C, and partitions D E F G, said partitions dividing 95 the interior of the body of said box into rectangular compartments, and each longitudinal partition D or E being provided in its top with

a notch, O, at the side of each compartment, the latter being provided with lining or filling blocks, substantially as set forth.

2. The box A, having cover B, tray C, and partitions D E F G, said partitions dividing the body of said box into rectangular compartments, and each compartment being provided with lining or filling blocks, substantially as and for the purpose set forth.

In testimony that I claim the foregoing as my invention I have hereto set my hand in the presence of two subscribing witnesses.

JOSEPH WIESBAUER.
